UNITED STATES PATENT OFFICE.

FRANK JOHNSON, OF DETROIT, MICHIGAN.

SPEED-CHANGING MECHANISM.

1,147,868.

Specification of Letters Patent. Patented July 27, 1915.

Application filed November 6, 1913. Serial No. 799,419.

To all whom it may concern:

Be it known that I, FRANK JOHNSON, a citizen of the United States, and a resident of Detroit, in the county of Wayne and State of Michigan, have invented a new and useful Speed-Changing Mechanism, of which the following is a specification.

This invention relates to means for changing the relative speeds of the crank shafts and of the propeller shafts of power-driven vehicles, and its object is to provide a simple and effective transmission mechanism which shall be controlled by a selecting device so constructed that it may be positioned at any time prior to the changing of the transmission gears.

This invention consists in combination with an indicator and a plurality of movable selector cams connected thereto, of a transmission gear shifting device comprising an operating member and a series of controllers adapted to engage the selectors, and gear shifters operated by said actuating member whenever their respective controllers are properly positioned by the selector.

In the accompanying drawings, Figure 1 is a side elevation of the case containing the controller and of the actuating mechanism. Fig. 2 is a rear elevation of one of the connections. Fig. 3 is a vertical section of a dog to control the actuating lever. Fig. 4 is a longitudinal section of the controller. Fig. 5 is a vertical section of the controller. Fig. 6 is a view of the controller cams arranged in two rows, the speed or positioning cams being in the upper row and the cams for causing the parts to be moved to neutral position being in the lower row. Fig. 7 is a vertical section of the transmission case and of the case for the controlling mechanism on the plane of the crank shaft. Fig. 8 is a detail of the reversing gear and shifter. Fig. 9 is a horizontal section of the case shown in Fig. 8 on the plane of the gear-shifting rods, the pedal shaft being broken away within the case. Fig. 10 is a plan of a steering wheel of an automobile.

Similar reference characters refer to like parts throughout the several views.

This invention is designed to facilitate the changing or the reversing of the speed of power-driven vehicles, and consists generally of an indicating device comprising a movable member which can be shifted by the driver in conjunction with a scale which

has characters indicating the relative speed and direction of movement. Fig. 10 shows how this device may be preferably mounted at the head of the steering post above the steering wheel. The changing of the gears, and thereby of the speed or direction of the vehicle, is preferably effectuated by the clutch pedal of the vehicle, which pedal during the first portion of its forward movement disengages the engine from the transmission gears and then, if desired, shifts the gear already in engagement to neutral position. At the beginning of the return movement of the clutch pedal the selected gears, if the speed or direction is to be changed, are shifted into engagement, and during the last portion of the return movement of the clutch pedal, the clutch is permitted to connect the crank shaft to the transmission gears so that the engine will be immediately coupled to the driving axle.

In the accompanying drawings, 6 represents the crank shaft of the engine to which is connected the drum 7 having a clutch ring 8. A transmission case 9 carries ball bearings 10 for the transmission main shaft 11, which connects to the propeller shaft 12 by means of a universal coupling 13, and the propeller shaft connects to the rear axle 85 of the vehicle in any desired manner. This case 9 also carries a ball bearing 14 for the transmission stub shaft 15, whose forward end has secured to it a disk 16, which carries the pins 17 that extend through the plate 18, forming the second clutch member. This plate is secured to a hub 19 against which the ring 20 is pressed by means of the usual crank arm 21, mounted on the shaft 23. The front end 24 of this stub shaft is guided to run concentrically with the crank-shaft 6 by means of the ball bearing 25.

Any desired means may be provided for connecting the shaft 23 to the pedal shaft 29 so that they will revolve together in the same direction. On this shaft 29 is secured a downwardly extending crank-arm 30 having a pin 31 extending through the slot 32 in the front end of the link 33. An adjustable stop 34 limits the forward movement of this link. A clamp 35 on this link receives the rear end of the tension spring 36, the forward end of which connects to the eye 37.

The rear end of the stub shaft 15 is enlarged and formed to constitute the gear 37^a

- that meshes with the gear 38^a on the countershaft 39^a. Secured to this countershaft are gears 40^a, 41^a and 42^a. The front end 44^a of the shaft 11 is journaled in roller bearing 45^a in the rear end of this stub shaft 15. On the shaft 11 is slidably splined the clutch member 46^a having internal teeth 47^a that are designed to engage the complementary teeth 48^a on the rear end of the stub shaft 15. It will be noticed that when this clutch member 46^a is moved to the right in Fig. 7, which is toward the front of the vehicle, that the stub shaft 15 and the shafts 11 and 12 will all be in direct engagement and revolute at the same speed. But if this clutch member 46^a is slid back until its gear teeth 50^a engage with the gear 40^a on the countershaft 39^a, then the gear 37^a on the intermediate shaft 15, which is in constant engagement with the gear 38^a on the countershaft, will drive this shaft 11 through the countershaft, the gear 40^a and the gear 50^a at a somewhat slower speed than the speed of the crank-shaft. These two speeds are known as the fourth and third speeds respectively.
- Slidably splined on the shaft 11 are two connected gears 52^a and 53^a, adapted respectively to mesh with the gears 41^a and 42^a on the counter shaft. When these gears 52^a and 53^a are shifted to the right until the gear 52^a engages the gear 41^a, the clutch 46^a being in the position shown in Fig. 7, then the intermediate shaft 15 will drive the shaft 11 through the gears 37^a, 38^a, 41^a and 52^a; but when the gear 53^a is in engagement with the gear 42^a, then the countershaft will drive the shaft 11 at its slowest speed. These two are known as the second and first speeds of this transmission, respectively.
- Loosely slidable and revolute on the reversing gear shaft 54^a, mounted in the case as shown in Fig. 8, are the connected reversing gears 55^a and 56^a. These gears are shifted to the right, in Fig. 7, toward the engine in the ordinary vehicle, until the gear 55^a meshes with the gear 53^a and the gear 56^a meshes with the gear 42^a. The other gears remain in the positions shown in Fig. 2. This engagement of the gears 42^a—56^a—55^a—53^a will cause the shaft 11 to turn in the opposite direction from the shaft 15.
- The details of the transmission thus far described form no part of the present invention, and any other proper transmission may be substituted therefor. The gears of this transmission may be shifted by means of the rods 60, 61 and 62, for respectively the reverse, the first and second, and the third and fourth speeds. It will be noted that only one of these rods should be shifted at any time from its neutral position, shown in Fig. 4, and for this reason, they are provided with grooves 64, into which the ends 65 of the interlocking bolts 66 enter when the next adjacent rod is shifted. These rods are slidable in transverse holes 67 and 68 in the case 9. Vertical holes in the case above these rods contain the guides 69, pins 70^a and springs 71^a, as shown in Fig. 7. The pointed lower ends of these pins enter the grooves 64 and holes 73 in these rods to hold them in any desired position. Collars 74^a, 75^a and 76^a on these rods carry the forks 77^a, 78^a and 79^a, respectively, whereby the gears 75 are connected to the rods. These rods 62, 61 and 60 connect to links 81, 82, 83, 84 and 85, which connect to the collars 86, 87, 88, 89 and 90, respectively, of the pairs of selector cams 70—76, 71—77, 72—78, 73—77 and 74—80 respectively, of the reverse, 1st, 2nd, 3rd and 4th speeds, respectively, by means of pins 96 that pass through the lugs 97 on these collars.
- Connected to the case 9 of the transmission is the case 98 of the selecting mechanism, which carries the bearings 97 and 100 of the gear shifting mechanism. Attached to this case 98 is a small case 101 for a connecting gear. The connecting rod 90 attaches to an arm 102 (Fig. 1) on the end of the hub 103 of the gear shifting drum 104, to which is secured a head 105 having a hub 106, journaled in the bearing 100. Rods 107 extend through holes in this drum and act as pivots for the dogs 108 mounted in pockets cut in the drum in the transverse planes of the collars 86 to 90 inclusive. These collars may be held in position by spring-rings 109. These dogs 108 are provided with inwardly turned noses 110 and tails 112 (Fig. 5) while compression springs 113 are mounted between the tails of the dogs and the still remaining portions of the drum. The collars 86 to 90 inclusive are provided with notches 115 and 116, the shoulders of which are shown to be about forty-five degrees apart. The bearing sleeve 124 for the trunnion 123 of the shaft 120 is mounted in the hub 103 of the drum 104, while the shaft 120 will pass through the hub 106 and have its outer end mounted in the bearing sleeve 121 in the outer cover 101 of the case 101. On this shaft 120 is secured a gear 125 which meshes with the segmental gear 126 on the shaft 127. The shaft 120 is provided with a key 118 on which the selector cams are mounted. These are formed of two designs, as shown in Fig. 6.
- The cams 70 to 74 inclusive differ only in the position of the key-seat 75, while the cams 76 to 80 inclusive again differ only in this manner. These cams are slid onto the shaft 120, in pairs, the cams of the upper row alternating with those of the lower, all positioned by the key 118, and each cam of the upper row being immediately to the left, in Fig. 4, of the one just below it in Fig. 6. As in the former application, the cams are all shown in their neu-

tral positions, and it will be noticed that each cam of the upper row has a low portion about sixty degrees in length, and the position of these low portions varies through about three hundred degrees of arc.

Mounted on the shaft 127 is a crank arm 130 which connects to the crank arm 132 by means of the link 133. This crank arm 132 is mounted and turned in any desired manner, but is preferably connected to the lower end of a shaft 134 mounted in the steering post, and an indicator 135 is preferably secured to the upper end of this shaft. A notched segment 136 may be secured to the steering post above the wheel 137 and be provided with notches opposite the characters R, N, 1, 2, 3 and 4, which denote reverse, neutral, 1st speed, 2nd speed, 3rd speed and 4th speed, respectively. The selector cams may therefore be properly positioned, according to the position of the indicator 135. The angular movement of the indicator will be multiplied by the gear 125 and segment 126, and, while any desired movement of the indicator and selector may be provided for, the mechanism shown is so constructed that a movement of the indicator from N to R will turn the selector sixty degrees to the left. By swinging the indicator to the notches marked 1, 2, 3 or 4, the selector will be turned sixty, one hundred twenty, one hundred eighty or two hundred and forty degrees, respectively. The different views show the selector at neutral position. The upper dog 108 for each collar is in the vertical plane of one of the cams 76 to 80 inclusive, called the "neutral" cams, while the lower dog 108 is in the plane of one of the cams 70 to 74 inclusive, called the "speed" cams. This is indicated in Fig. 4. The "reverse" cams must be turned to the left a distance of 60 degrees to bring them to operative position. The "first" speed cams 71 and 77 must be turned 60 degrees to the right; the "second" speed cams 72 and 78 must be turned 120 degrees to the right; the "third" speed cams must be turned 180 degrees to the right; and the "fourth" speed cams must be turned 240 degrees to the right, to bring these particular cams to operative position. Each of these distances are indicated by dotted lines in Fig. 6. When each of the "neutral" cams has been turned its proper distance, its high spot will be under the nose of its dog and extend about 45 degrees to the right, and prevent the tail of this dog from engaging the shoulder 115 of its collar. But the upper dogs of all the other collars are not held inoperative but may all engage the shoulders 115 of their respective collars and turn such collars to neutral. The only one of the collars and gear shifting links (81 to 85 inclusive) which will not be moved to neutral will be

the collar and link of the speed selected. At the same time, the proper "speed" cam will be turned a proper distance and its low portion will be under the nose of its dog. All the other dogs will have their noses in contact with the high portions of their cams and their tails will thereby be held out of engagement with the shoulders 116 of their collars. Because of the length of the high portions of the "neutral" cams and of the low portions of the "speed" cams, there is no danger of any change in position of the dogs during either stroke of the crank arm 102.

The slot 42 in the crank arm 102 is inclined to the line of the arm, and receives the pin 43, carried by the rear end of the link 33. The crank arm 102 has a lug 45, shown in Fig. 2, adapted to engage the adjustable stops 46 and 47, on the case 98. The distance between these stops is such that the actuator hub 104 will be turned the proper distance at each movement of the clutch pedal.

It will be noticed that the lower dogs 108 operate on the return stroke of the crank arms 30 and 102, and that when the tail of the selected dog is left in contact with the shoulder 116 of its actuating collar, and the dog is under pressure from the spring 36, considerable force will be required to turn the selector cam which happens to be engaged because of the friction between the tail of the dog and the shoulder 116. To obviate this friction, it is desirable to move the crank arm 102 a short distance forward, sufficient to disengage the dog and shoulder 116. The mechanism to accomplish this is shown in Figs. 1 and 3.

A round lug 49 on the case 98 carries a pin 50, on which an eccentric collar 51 is held by the nut 52, in such a manner that the collar can be adjusted to raise or lower the lower end of the pawl 53 carried by the collar. A lug 54 carries an adjustable stop 55, against which the pawl is normally held by the spring 56. A bolt 57 secures the cam 58 to the link 33. The operation of this device is as follows: When the link 33 is forced back (to the right in Fig. 1) the pin 43 slides down to the lower end of the slot 42 in the crank arm 102 and swings this arm until the lug or fin 45 on the crank arm 102 engages the stop 47. This movement causes all but the selected gears of the transmission to be moved to neutral position. During this rearward movement, the cam 58 may engage the pawl 53 and swing it back, but after the cam has passed the lug, the latter will be returned by the spring 56. Upon the return or forward movement of the link under action of the spring 36 or the crank arm 30, the arm 102 will swing forward until the lug 45 engages the stop 46. This is the movement whereby the lower dogs 108

carry the collars 86 around to the left and are left with their tails in engagement with the shoulders 116. Toward the end of this forward movement, the cam 58 passes below the pawl 53, which causes the pin 43 to be so far down the slot 42 from the shaft 103 that the arm 102 engages the stop 46 and thus makes a full stroke. When the cam 58 has passed this dog, the spring 36 will tend to swing up the rear end of the link 33, the front end being substantially stationary because of the pin 31 and stop 34. This upward movement of the rear end of the link causes the pin 43 to slide up in the inclined slot 42 and to press back the lower end of this crank arm, as shown in Fig. 1, and thereby causes the disengagement of the tail of the dog 108 from the shoulder 116. The selector can now be turned freely.

Referring now to Fig. 7, it will be remembered that the drum 104 is turned by the arm 102 and carries the dogs 108 with it. The distance is about thirty degrees, first to the right and then to the left. All the "neutral" cams 76 to 80 are shown in Fig. 6 in neutral position, and it will be seen that at the beginning of their movements, each of the teeth 110 of the upper dogs will drop, if it has not already dropped, the tail of each dog being swung out by its spring 113. If the "3rd speed" gears are in engagement, the rod 62 will be at the left end of its movement and the collar 87 will be turned to the left nearly thirty degrees and the collar 86 the same distance to the right. At the movement of the crank arm 102 to the right, the upper dog 108 will immediately engage in the notch 115 of the collar 87 and turn it to the right, to the position shown in Fig. 5. This movement of the collar 87 will result in the collar 86 being turned an equal distance to the left, because of the connection of the two collars to the rod 62 by means of the links 81 and 82. In a similar manner, should the rod 62 and the gear-clutch 46 be in their "4th speed" position, that is, at the right end of their movement, the collar 86 will have been turned to the left, and will be turned back to the right by means of its upper dog 108 and by the drum 104 to shift the gear-clutch to neutral. The same action occurs when the 1st and 2nd speed gears are to be shifted to neutral position. When the reverse gears are in mesh, the rod 60 is at the right end of its movement and the collar 90 is turned to the left. Therefore, when the selector is at neutral position, the upper dog will turn its collar to the right and slide the reverse gears to the position shown in Fig. 7. It will be evident that if the transmission gears are set for any speed and it is desired to change to another, that the gears in mesh must be shifted to neutral. To effect this, the various cams shown in Fig. 6 are provided with high and low portions. In con-

sidering this mechanism it may be remembered that the cams shown in Fig. 6 turn in the same direction to and from neutral as the indicator 135 in Fig. 10. If now the reverse gear is in mesh and it is desired to change to the 1st speed, the indicator is swung to the notch "1". This will turn the selector cams thirty degrees to the right from the positions shown in Fig. 6. At the forward movement of the arm 102 and the turning of the drum 104 to the right, the nose of the upper dog of the cam 77 will ride on the high part of this cam and the dog will have no effect on the collar 89, but the nose of the upper dog of the reverse cam 70 will ride on the low portion of the cam and its tail will engage the notch 115 of the collar 90 and turn this collar to the right and so shift the reverse gears 55 and 56 to the left, that is, to neutral. At the end of this movement, the tail of the lower dog of the cam 77 will reach the notch 116 of the collar 89, and as the nose of this dog is nearly against the low portion of the cam 77, the collar 89 will be turned to the left, forcing the rod 61 to the left and the gear 53 into mesh with the gear 42 on the countershaft. The cam 78, which coördinates with the collar 88, is so formed that its lower dog is held out of engagement with its notch 116 during the time the rod 61 is being shifted by the arm 102. When the cam 78 is turned one hundred and twenty degrees to the right, then the noses of the upper dogs of all the units except 78 engage low portions of their respective cams and thus shift the rods 60, 61 or 62 to neutral if not already there. At the return of the arm 102 the nose of the lower dog rides on the low portion of the cam 78, and its tail will engage the notch 116 of the collar 88, turning the collar to the left and forcing the rod 61 to the right by means of the link 83, thus obtaining second speed. When the third speed is desired, the selector is turned one hundred and eighty degrees to the right. This brings the low portion of the cam 79 under the nose of its upper dog, and as the collar 88 had been left turned to the right, when the arm 102 is swung, the tail of this dog will engage the notch 115 and the collar will be turned to neutral position. In this case as in all others, the upper dog returns the collar to neutral position. The lower dog always does the positioning. As the 3rd speed is desired, the upper dog of cam 79 will ride inoperatively on the high portion of this cam, so that, if the 3rd speed were already in use, it would not be brought back to neutral. But on the return stroke, the nose of the lower dog will ride on the low portion of the cam 73 and the tail of the dog will engage in the notch 116 of the collar 87 and turning this collar to the left, pull the rod 62 to the left, thus obtaining third speed. In a similar manner the nose of the 120

lower dog of cam 74 will ride in the low portion and therefore engage the notch 116 of the collar 86, forcing the rod 62 to the right. So long as the vehicle is running at the speed specified by the indicator, any back and forth movement of the clutch-pedal is without effect on the transmission gears, for the upper dog of the selector for that speed is held out of operation. But if the indicator is shifted to any other position, the transmission gears just previously employed will be shifted to neutral at the next forward movement of the clutch-pedal. The shifting of the selected gears to operative position is preferably accomplished by means of a spring 36 connecting to the link 33 and any fixed support. This spring will normally shift the gears in advance of any thrust from the crank arm 30. But in case the shifting gears should be so positioned that their teeth abut end to end with the co-operative gears, the jamming action of the arm 30 will assist the spring 36 to cause the ends of the teeth to engage, after which the spring 36 will continue to slide the shifted gears along to full engagement. The proportions and adjustments of the parts are such that the main clutch of the engine will not begin to engage until the shifted gears have about one-half the lengths of their teeth in engagement with the teeth of the co-operative gears.

Many changes in the proportions and arrangements of the parts can be made by those skilled in the art without departing from the spirit of my invention.

I claim:

1. In a speed changing mechanism, the combination of operating devices for shifting the gears of a power transmitting device, each embodying a revoluble collar and a connecting rod, a revoluble actuator, a series of pairs of dogs carried thereby, one pair for each operating device, one dog of each pair adapted to move a shifting rod to neutral position and the other dog to move said rod and the gears connected thereto to operative position, and a selecting cam for each of said dogs.
2. In a speed changing mechanism, the combination of a plurality of collars and a connecting rod for each collar, a revoluble actuator, a series of pairs of dogs carried thereby, one pair for each operating collar, one dog of each pair adapted to move a collar and the gears connected thereto to neutral position and the other dog to move said collar and the gears connected thereto to operative position, and a cam to properly position each dog.

3. In a speed changing mechanism, the combination of a plurality of gear shifting collars, each adapted to be revolved in both directions from neutral position, a revoluble actuator, a series of pairs of dogs carried

thereby, one pair for each collar, one dog of each pair adapted to move its collar and the gears connected thereto to neutral position and the other dog to move said collar and the gears connected thereto to operative position, a selecting cam for each dog, and means for positioning the selecting cams. 70

4. In a speed changing mechanism, the combination of a plurality of gear shifting devices, each adapted to be moved in both 75 directions from neutral position, a revoluble actuator, a series of pairs of dogs carried thereby, one pair for each operating device, one dog of each pair adapted to move the device to neutral position and the other dog 80 to move said device to operative position, a selecting cam for each dog, and means for positioning the selecting cams.

5. In a speed changing mechanism, the combination with a plurality of gear shifting collars, a drum on which the collars are mounted, a pair of dogs for each collar mounted on the drum, each dog adapted to turn the collar in one direction, a selector concentric with the collars and drum to 90 control the operation of the dogs and comprising a cam for each dog, and means for positioning said selector.

6. In a speed changing mechanism, the combination of a hollow operating drum 95 having a series of pairs of transverse slots, longitudinal pivot rods extending across the slots, dogs mounted in said slots on said pivot rods and constituting pairs, a collar mounted on the drum in the planes of each 100 pair of dogs and formed to be engaged by the dogs, a rotatable selector mounted within the drum comprising cams, one for each dog, said cams engaged by the dogs to predetermine the positioning of the dogs. 105

7. In a speed changing mechanism, the combination of a hollow operating drum having a series of pairs of transverse slots, longitudinal pivot rods extending across the slots, dogs mounted in said slots on said 110 pivot rods and constituting pairs, a collar mounted on the drum in the planes of each pair of dogs and formed to be engaged by the dogs, a rotatable selector mounted within the drum and engaged by the dogs 115 and consisting of a series of cams united side by side, one for each dog, said cams having high and low portions, the high portions of one cam of each pair being of the same length as the low portion of the 120 other, said cams adapted to predetermine the positioning of the dogs and collars.

8. In a gear changing device, the combination of collars, each adapted to be turned in both directions from neutral position, a revoluble hollow drum on which the collars are mounted, a series of pairs of dogs carried thereby, one pair for each collar, one dog of each pair adapted to move the 125 collar to neutral position and the other dog 130 to move said collar to operative position.

to move said collar to operative position, a rotary selector mounted within said drum and comprising a series of cams on a shaft, one cam for each dog in engagement with 5 said dogs to position the same, and means to turn the shaft.

9. In a speed changing mechanism, the combination of an indicator, a selector connected thereto, a drum in which said selector 10 is mounted, dogs pivotally mounted in the drum, a series of collars on the drum and having a series of internal notches which may be engaged by the dogs to revolve the collars, a slotted crank-arm connected to the 15 drum, a pin slideable in the slot, a link connected to said pin, an operating arm connected to the link to turn the crank-arm and drum in one direction, and a spring to move the pin in the slot to turn the drum 20 in the opposite direction.

10. In a speed changing mechanism, the combination of an actuating drum, a crank arm connected thereto and having an inclined slot in its outer end, a pin in said 25 slot, a link connected to said pin, an operating arm connected to the link to turn the crank-arm and drum in one direction, and a spring to move the pin in the slot to swing back the crank-arm.

11. In a speed changing mechanism, the combination of a revolute member, a crank-arm connected thereto and having an inclined slot in its outer end, a pin mounted 35 in the slot, a link connecting at its rear end to said pin, operating means connected to the link at its front end to swing said link and crank-arm in one direction, a spring connected to said link to move the link in the opposite direction, the line of the spring 40 being such that after the front end of the link has come to rest, the rear end will be swung by the spring that the pin will move in the slot and swing back the crank-arm.

12. In a speed changing mechanism, the 45 combination of a revolute member, a crank-arm connected thereto and having an inclined slot in its outer end, a pin mounted in the slot, a link connecting at its rear end to said pin, operating means connected to 50 the link at its front end to swing said link and crank arm in one direction, a spring connected to said link to move the link in the opposite direction, the line of the spring being such that after the front end of the 55 link has come to rest, the rear end will be so swung by the spring that the pin will move in the slot and swing back the crank arm, and means to prevent the rear end of the link from swinging under the pull of the 60 spring until the front end has come to rest.

13. In a speed changing mechanism, the combination of a revolute member, a crank-arm connected thereto and having an inclined slot in its outer end, a pin mounted 65 in the slot, a link connected at one end to

said pin, operating means connected to the opposite end of the link and adapted to move the arm and link in one direction, a spring connected to the link to move it in the opposite direction and to swing it to 70 move the pin in the slot and thereby move back the arm after the opposite end of the link has come to rest, and a pivoted pawl adjacent the link to prevent the movement of the pin in the slot until the arm and link 75 have reached the limit of their movement in one direction.

14. In a speed changing mechanism, the combination of a plurality of gear shifting rods, each adapted to be shifted longitudinally in both directions from neutral position, operating devices for shifting said rods, each embodying a revolute collar and a connecting rod, a revolute actuator, a series of pairs of dogs carried thereby, one 80 pair for each operating device, one dog of each pair adapted to move a shifting rod to neutral position and the other dog to move said rod and the gears connected thereto to 85 operative position, and a selecting 90 mechanism for said dogs.

15. In a speed changing mechanism, the combination of a plurality of gear shifting rods, each adapted to be shifted longitudinally in both directions from neutral position, operating devices for shifting said 95 rods, each embodying a revolute collar and a connecting rod, a revolute actuator, a series of pairs of dogs carried thereby, one pair for each operating device, one dog of each pair adapted to move a shifting rod to neutral position and the other dog to move said rod and the gears connected thereto to 100 operative position, and a cam to properly 105 position each pair of dogs.

16. In a speed changing mechanism, the combination of a plurality of gear shifting rods, each adapted to be shifted longitudinally in both directions from neutral position, operating devices for shifting said rods, each embodying a revolute collar and a connecting rod, a revolute actuator, a series of pairs of dogs carried thereby, one pair for each operating device, one dog of each pair 110 adapted to move a shifting rod to neutral position and the other dog to move said rod and the gears connected thereto to operative position, a selecting mechanism for said dogs, and an indicator for positioning the 115 selecting mechanism.

17. In a speed changing mechanism, the combination of a plurality of gear shifting rods, each adapted to be shifted longitudinally in both directions from neutral position, operating devices for shifting said rods, each embodying a revolute collar and a connecting rod, a revolute actuator, a series of pairs of dogs carried thereby, one pair for each operating device, one dog of each pair 120 adapted to move a shifting rod to 125

neutral position and the other dog to move said rod and the gears connected thereto to operative position, a selecting mechanism for said dogs, an indicator for positioning the selecting mechanism, and a graduated bar adjacent said indicator.

18. In a speed changing mechanism, the combination with a plurality of rods for shifting the transmission gears of a vehicle, links for shifting each of said plurality of rods and the gears connected thereto to and from neutral position, collars to which said links are connected, a revolute actuator, dogs carried thereby, and a selector for positioning said dogs and thereby determining the collar to be revolved and its direction of revolution.

19. In a speed changing mechanism, the combination with a plurality of rods for shifting the transmission gears of a vehicle, links for shifting each of said plurality of rods and the gears connected thereto to and from neutral position, collars to which said links are connected, a revolute actuator, dogs carried thereby, and a selector for positioning said dogs comprising a series of connected cams, one for each link, which cams determine the collar to be revolved and its direction of revolution.

20. In a speed changing mechanism, the combination with a plurality of rods for shifting the slide gears of a vehicle transmission, of a pair of links connected to each of said plurality of said rods, each link of each pair adapted to shift the rod and gears connected thereto longitudinally into engaging position at one side of neutral, a

revolute collar connected to each link, a drum on which said collars are mounted, engaging members for each collar mounted on the drum, a selector to predetermine the collar and its direction of movement by said drum, and means to oscillate the drum.

21. In a speed changing device, the combination of an indicator, a plurality of selector cams connected thereto, and a transmission-gear shifting device comprising an operating member, a series of controllers adapted to engage the selectors, and gear engaging members actuated by said operating member whenever the proper controllers have been properly positioned by the selector.

22. In a gear changing device, the combination of a plurality of gear shifting rods, each adapted to be shifted longitudinally in both directions from neutral position, operating devices for shifting said rods, each embodying a revolute collar and a connecting rod, a revolute hollow drum, a series of pairs of dogs carried thereby, one pair for each operating device, one dog of each pair adapted to move a shifting rod to neutral position and the other dog to move said rod and the gears connected thereto to operative position, and a rotary selector mounted within said drum.

In testimony whereof I have signed this specification in the presence of two subscribing witnesses.

FRANK JOHNSON.
